(57)

CLAIM

(22) Filed: **Jan. 15, 2018**

The ornamental design for a horizontal positioning ruler, as shown and described.

(30) **Foreign Application Priority Data**

Nov. 7, 2017 (CN) 2017 3 0543047

DESCRIPTION

(51) **LOC (12) Cl.** **10-04**

FIG. 1 is a perspective view showing my design;
FIG. 2 is a front view showing my design;
FIG. 3 is a back view showing my design;
FIG. 4 is a left side view showing my design;
FIG. 5 is a right side view showing my design;
FIG. 6 is a top plan view showing my design; and,
FIG. 7 is a bottom plan view showing my design.

(52) **U.S. Cl.**

The broken lines in the drawings depict parts of the horizontal positioning ruler that form no part of the claimed design.

USPC **D10/71; D10/65**

(58) **Field of Classification Search**

USPC D10/65, 71
